(57) **CLAIM**

The ornamental design for a tumbler, as shown and described.

DESCRIPTION

FIG. 1 is a top perspective view of a tumbler showing our new design;

FIG. 2 is a bottom perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is a top perspective view of a lid of the tumbler shown in FIG. 1, shown removed for ease of illustration;

FIG. 10 is a left side elevational view thereof;

FIG. 11 is a bottom plan view of a top cover assembly without a threaded base;

FIG. 12 is a top perspective view of the tumbler of FIGS 1-8, without the top cover assembly, shown removed for ease of illustration;

FIG. 13 is a bottom perspective view thereof;

FIG. 14 is a front elevational view thereof;

FIG. 15 is a rear elevational view thereof;

FIG. 16 is a right side elevational view thereof;

FIG. 17 is a top plan view thereof;

FIG. 18 is a bottom plan view thereof;

FIG. 19 is a top perspective view of the lid of the tumbler shown in FIG. 1, without the top cover assembly, shown removed for ease of illustration;

FIG. 20 is a top plan view thereof; and,

FIG. 21 is a front elevational view thereof.

The left side elevational view of the tumbler shown in FIGS. 12-18 is not shown, as the claimed subject matter is identical to the right side elevational view shown in FIG. 16.

(Continued)

The broken lines shown in the drawings depict environmental subject matter that forms no part of the claimed design.
